Application October 23, 1942, Serial No. 463,124

3 Claims. (Cl. 131—34)

This invention relates to cigarette making machines and more particularly to a machine of this character for making cigarettes in comparatively small quantities for immediate use.

One of the important aims of the instant invention is the provision of a small, compact and sturdily built machine that is fully capable of delivering therefrom perfectly rolled cigarettes as long as a supply of paper and tobacco is maintained in the machine.

A further aim of the invention is to provide a machine requiring a minimum amount of manual manipulation for rolling a cigarette.

A yet further aim of this invention is the provision of a cigarette making machine wherein the mechanism for carrying out the several steps necessary to roll a cigarette is so arranged and related that substantially uniform power is required throughout a complete cycle of operation of the machine.

Minor objects will appear during the course of the following specification, reference being had to the accompanying drawings wherein:

Fig. 1 is a perspective view of a cigarette making machine constructed in accordance with this invention.

Fig. 2 is a front elevational view of the machine with the end and cover members together with the receiving tray removed therefrom to better disclose the operating mechanism.

Fig. 3 is an elevational view of the crank side of the cigarette making machine, the parts being shown in position assumed at the beginning of the operation for forming a cigarette.

Fig. 4 is a top plan view of the machine with the end and cover members removed.

Fig. 5 is a bottom plan view.

Fig. 6 is an elevational view of the side of the machine opposite the crank.

Fig. 7 is a cross section on the line VII—VII of Fig. 2 with the parts in the same position as shown in the preceding figures.

Fig. 8 is a similar section with the parts in slightly advanced position from that shown in Fig. 7.

Fig. 9 is a like section with the parts in the position assumed immediately after the knife has cut the paper for a cigarette.

Fig. 10 is a cross section on the same line as Fig. 7, showing a cigarette rolled almost to completion.

Fig. 11 is a fragmentary section taken on line XI—XI of Fig. 2.

Fig. 12 is a fragmentary elevational view of

the ratchet and pawl mechanism partly obscured in Fig. 3.

Fig. 13 is a sectional view taken on line XIII—XIII of Fig. 4 looking in the direction of the arrows.

Fig. 14 is a fragmentary section taken on line XIV—XIV of Fig. 9.

Fig. 15 is a cross section of the paper feeding mechanism taken on line XV—XV of Fig. 8.

Fig. 16 is a side elevational view of a knife control arm.

Fig. 17 is a vertical section on the same line as Fig. 7 showing only a few related parts for controlling the flow of tobacco from a supply hopper.

Fig. 18 is an edge elevational view of the parts shown in Fig. 17.

Fig. 19 is a fragmentary section taken on line XIX—XIX of Fig. 6.

Fig. 20 is a sectional view taken on line XX—XX of Fig. 19 looking in the direction of the arrows; and

Fig. 21 is a fragmentary perspective view of the crank.

Referring in more detail to the drawings, numerals 22 and 24 designate side plates held in fixed spaced relation by a plurality of spacers 26 having threaded end sockets aligned with openings 28 (Fig. 5) in the side plates for receiving screws 30 which are provided with elongated heads 31 for a purpose later to be disclosed.

A plurality of cross plates in addition to their primary function, further assist in retaining plates 22 and 24 in fixed spaced relation and include parallel, vertically disposed hopper plates

32, a bottom plate 34 for the hopper, and a horizontally disposed plate or table 36. Each of these plates (Figs. 3 and 6) is preferably provided with ears 38 seated in slots 40 of the side plates, thus producing a strong, rigid frame for

the machine when the cross plates and spacers are clamped securely between the side plates. A cavity 42 formed by the vertical cross plates 32 and side plates 22 provides a supply hopper for tobacco 44.

The lower ends of plates 32 are spaced from the bottom plate 34 to allow sliding movement therebetween of a discharge plate or plunger 46 for moving a measured quantity or load of tobacco, sufficient for making one cigarette through

an outlet opening 47 upon each reciprocation of this plate. Actuation of the discharge plate 46 is accomplished by means of a hand crank 48 removably mounted on one end of a shaft 50 which has spaced portions thereof journaled in the side plates 22 and 24. A pair of spaced crank

arms 52 having inwardly directed crank pins 54 are keyed on the shaft 50 as shown at 56.

Fixed on a rock shaft 58, positioned below shaft 50 are a pair of arms 60 with their upper notched ends 62 engaging the crank pins 54 and constricted lower ends 64 seated in openings 66 of the discharge plate. Thus, upon downward movement of the crank 48 the discharge plate slides forwardly on the bottom 34 carrying a charge or load of tobacco from the hopper. Slots 68 in the bottom 34 (Fig. 5), provide clearance for the lower ends of the arms 60 throughout their arcuate path of travel. From Fig. 14 it will be observed that the hopper plate 32 nearest the front of the machine has a serrated lower edge 70 which is provided to facilitate the discharge of relatively "long shredded" tobacco from the hopper 42.

Outlet opening 47 is normally closed by a gate 72 maintained in sliding relation with the serrated hopper plate 32 by a headed pin 74 fixed in said plate and engaging a vertical slot 76 in the gate. A forwardly directed flange 78 of the gate is seated in notched ends 80 of a pair of spaced arms 82 and 84, keyed on a cross shaft 86 which has its reduced ends journalled in side plates 22 and 24. Arm 82 limits the vertical path of travel of gate 72 by engagement of its notched forward end 88 with a stop pin 90 fixed in side plate 22 (Fig. 11). A spring 92 anchored to the side plate and secured to arm 82 normally maintains gate 72 in its lowermost position.

In order to raise gate 72 in properly timed relation with actuation of the discharge plate, mechanism operably connected with arm 84 is provided and includes a cam member 94 pivotally mounted on a stub shaft 96 fixed in side plate 24. The shape of arm 84 may be readily determined from Fig. 17 and a roller 98 on the upwardly directed end 100 of said arm is engaged by a cam segment 102 of cam member 94, as clearly shown in Fig. 7. A finger 104 of the cam member is in turn engaged by stud 106 fixed to and projecting laterally from a bell crank lever 108 through an opening 110 provided in side plate 24. Bell crank lever 108 (Fig. 6) is in fixed relation with shaft 50 whereby rotation of said shaft in a counter-clockwise direction, as viewed in Fig. 3, will depress finger 104 and cause gate 72 to be raised. Finger 104 is normally held in a raised position by spring 105. When stud 106, during the course of its downward movement, rides over the end of finger 104, cam member 94 instantly returns to its initial position under action of spring 105. Spring 92 then quickly forces gate 72 to its lowermost point of travel, thereby closing the discharge opening and shearing any tobacco shreds which may have lodged in the serrations 70.

Tobacco discharged from the outlet opening 47 is deflected to a desired path of travel by a vertically movable shield 112 provided with a guard portion 114 in sliding relation with gate 72. At its lowest point of travel the guard portion 114 is substantially coextensive with the gate 72 when the latter is in its lowermost position, the guard portion being moved to this point slightly ahead of the gate, as will later be more fully described.

Means for supporting the shield 112 comprises a U-shaped member 116 mounted for free pivotal movement between arms 82 and 84 on cross shaft 86. Figs. 2 and 4 most clearly show U-shaped member 116 in its entirety and free ends 118 of said member are apertured to receive ears

120 of shield 112 (Fig. 2), whereby the shield is loosely hung between the ends of member 116 with its guard portion 114 urged against gate 72 by a spring 122, the ends of which are respectively secured to the upper end of shield 112 and member 116.

Pivoting of U-shaped member 116 on cross shaft 86 to raise and lower shield 112 is effected through the medium of a notched plate 124, freely movable on cross shaft 86 but pinned to a depending ear 126 of member 116, as shown at 128, to create a fixed relation between said latter member and plate 124. Stud 106, previously referred to, moves into a notch 130 of plate 124 upon downward movement of crank 48, thereby lowering shield 112. It is desirable however, to have shield 112 drop rapidly toward the end of its downward movement in order to cover outlet opening 47 shortly before gate 72 reaches its lowermost point of travel. A control arm 132 is provided for this purpose and is pivotally mounted on stub shaft 96. One end of said arm 132 is resiliently anchored by a spring 134 to side plate 24, thus urging the opposite end of the arm against a lateral projection 136 on U-shaped member 116. The point of contact of arm 132 with projection 136 is in the form of a W-shaped notch 138 having a peak 140. Accordingly, when projection 136 passes peak 140, shield 116 will drop instantly, being limited in its downward travel by engagement of projection 136 with the lower face of notch 138.

In order to catch a measured quantity of tobacco, discharged from the hopper 42 by plate 46, a relatively wide tape 142 is mounted in the lower portion of the machine with its front end looped over a cross pin 144 and its rear end similarly secured to cross pin 146. Both pins 144 and 146 have their ends fixed in side plates 22 and 24, as will be apparent. Tape 142 is of a width substantially equal to the spacing between side plates 22 and 24 and may be formed of any suitable flexible material such as rubberized cloth or the like. An intermediate portion of tape 142 overlies table 36 with a considerable amount of slack left in the remaining portion for a purpose later to be disclosed.

Table 36 provides the necessary planar surface whereon paper may be spread and a charge of tobacco carried to be rolled into a cigarette. A spool 148 for carrying a supply of cigarette paper 150 is mounted immediately below table 36 for free rotative movement in a U-shaped bracket 152 having legs 154 formed with notched ends to receive end trunnions 156 of the spool. Blade springs 158 are fixed to legs 154 and provided with suitable apertures 160 to receive trunnions 156 for retaining spool 148 in its mounting bracket, and to apply the required tension to the roller to maintain the paper in tautened condition. Paper from spool 148 is threaded through an opening 162 in side plate 24, around a feed roller 164 (Figs. 6 and 15) and between said feed roller and a tensioning roller 166, both feed and tensioning rollers being mounted between spaced bearing brackets 168 on shafts 170 and 172 respectively. Said bearing brackets are secured to side plate 24 and each bracket carries a pin 174 whereon is anchored one end of a light tensioning spring 175, the opposite end of the spring being attached to a projecting end of shaft 172.

The cigarette paper 150, after being passed between rollers 164 and 166 is threaded back

through plate 24 and over a cutter bar 176. Said cutter bar is preferably detachable for resharpening and may be fixed to an angle plate 178 secured as by screw 180 to side plate 24.

A length of paper equivalent to the length of a cigarette must be fed onto tape 142 with each downward movement of crank 48. Such periodic feeding of paper 150 is accomplished with mechanism including a combined ratchet and gear wheel 182 freely rotatable on the sleeve portion 184 of a lever 186 pivoted on a trunnion 188 which is fixed to and projects laterally from side plate 24. Lever 186 is connected to bell crank lever 108 by a link 190, and carries a pawl 192 which is urged to engagement with the ratchet portion of wheel 182 by a spring 194, as clearly shown in Fig. 20. Shaft 170 has its extended end journalled in bearing 196 on side plate 24 and fixed on the shaft is a gear pinion 198 meshing with the gear portion of wheel 182. The gear ratio of pinion 198 and gear wheel 182 is such that a quarter turn of said gear wheel resulting from each downward movement of crank 48 will turn feed roller 164 the required amount to advance the exact length of paper needed for rolling a cigarette.

Immediately after the proper length of paper is moved onto the wide tape 142, it is severed from the supply on spool 148 by a knife 200 passing along cutter bar 176. Knife 200 is pivotally secured to side plate 24 by a screw or like means 204 and is operably connected with its control arm 206 by a toggle link 208. Arm 206 and link 208 are respectively pivoted on studs 210 and 212 which project laterally from side plate 24. Pins 214 and 216 on knife 200 and arm 206 respectively, are seated in notches 218 formed in opposite ends of link 208. The screw 204 and pin 214 are further connected by a link 219. The relatively long end 220 of actuating arm 206 is in the path of travel of stud 106 but is not engaged by the stud until the latter is approaching its lower limit of travel. After severing the paper, the knife 200 is returned to its original position by a spring 222 having its respective ends affixed to side plate 24 and arm 206.

Referring to Fig. 8, it will be noted that a charge of tobacco forced from hopper 42 falls into a pocket 224 created by the slack in tape 142. Such slack is normally maintained by a spring tensioned roller 226 whereon is wound a pair of narrow tapes 228 (Fig. 5). One end of each of the narrow tapes is secured to roller 226 and the opposite ends are anchored together with wide tape 142 to cross pin 146. At a point intermediate its ends, the narrow tapes 228 are stitched or otherwise fastened to the wide tape as shown at 230.

Uniquely arranged rollers 232 and 234 combine with tape 142 to roll a charge of tobacco into a cigarette during the return or upstroke of crank 48. Roller 232 having shaft ends 236 extended through elongated primarily horizontal slots 238 in both side plates 22 and 24, is designed to travel ahead of roller 234 during the cigarette rolling operation and serves principally to retain the severed length of paper 150 in proper position above table 36. Roller 234 likewise has shaft ends 240 projected through slots 238 and normally rests near the rear end of narrow portions 239 of said slots which terminate at an angle from the horizontal. The relatively narrow portions form stops 242 (Fig. 10) for the forward roller 232. Fig. 7, for example, clearly illustrates that roller 234 lies beneath tapes 142 and 228 and is preferably provided with grooves 244 of sufficient width

and depth to receive the narrow tapes 228 so that tape 142 engages an uninterrupted, smooth surface along the entire length of said roller. Paper 150 is fed through one of the slots 238, as shown in Figs. 7 and 15. As roller 234 is carried forward by means presently to be described, it rides beneath tape 142 thereby forming a loop in the tape which rolls the charge of tobacco above table 36 and onto paper 150, as best shown in Fig. 10. Narrow tapes 228 are drawn forwardly by roller 234 and the necessary additional length is unreeled from tensioned roller 226. Continued forward travel of roller 234 carries the finished cigarette to an inclined portion 246 of tape 142 from whence it drops into a tray 248 or other suitable receptacle. During return of rollers 232 and 234 to their original position, slack in wide tape 142 is taken up by rewinding of narrow tapes 228 on spring-tensioned roller 226, thereby again forming a pocket for the next charge of tobacco falling from the supply hopper.

The mechanism for carrying the rollers forwardly in slots 238 and for returning them to their position of rest, will now be described. Shaft ends 236 of roller 232 are connected by links 250 (Figs. 3 and 6) to an arm 252 on the crank side of the machine and to an arm 254 on the opposite side. The upper ends of both arm 252 and 254 are keyed to extended ends of shaft 256 journalled in side plates 22 and 24. Similarly, shaft ends 240 of roller 234 are connected by links 258 to the lower ends of arms 260 and 262 adjacent side plates 22 and 24 respectively. A cross shaft 264 pivoted in said side plates, receives the upper ends of arms 260 and 262, both of which are keyed to the cross shaft for simultaneous movement therewith. Links 258 have laterally directed ears 266 provided with cross pins 268 for travel in slots 278. The shaft ends 240 and cross pins 268 also carry guards 272 (Fig. 10), one of which lies adjacent the inner face of plate 22 and the other against plate 24, the purpose of these guards being to prevent loss of tobacco through slots 238. Each of these guards includes a link portion 269 for connecting the inner end of cross pin 268 with shaft end 240.

Referring again to crank 48, it will be noted that this crank is not keyed directly to shaft 50 but is in fixed but readily detachable relation therewith through the medium of a crank plate 274 clearly illustrated in Fig. 12. An aperture 276 in crank plate 274 receives crank pin 54 projecting through an arcuate slot 278 in side plate 22, thereby interconnecting one of crank arms 52 with plate 274. The opposite crank arm 52 is interconnected in the same manner to bell crank lever 108 (Fig. 6). Crank plate 274 is provided with pin 280 for travelling in a relatively large arc about the axis of shaft 50 and with a pin 282 for moving through a smaller arc.

In the path of travel of pin 280 is an extension 284 (Figs. 3 and 13) of a plate 286 pivotally mounted on a stud 288 which is secured in side plate 22. A second extension 290 of plate 286 is connected by a link 292 to arm 260, and a third extension 294 of said plate is connected to one end of an expansion spring 296 which has its opposite end attached, as at 298, to side plate 22. Also projecting into the path of travel of pin 280 is a finger 300 pivotally secured to plate 286 with one end bearing against a collar 302 of said plate and held in such position by a spring 304 (Fig. 13). Thus, when crank plate 274 is rotated in an anti-clockwise direction as viewed in Fig. 3 upon downward

movement of crank 48, pin 280 depresses and rides over finger 300 and strikes extension 284 to rotate plate 286 in a clockwise direction to insure that roller 234 has been returned to the extreme rear end of slots 238. The movement of plate 286 just described will be possible only if spring 296 has failed to fully return roller 234. Clockwise rotation of crank plate 274 incident to return movement of crank 48, will cause pin 280 to engage the lower face of finger 300, thereby moving plate 286 in a counter-clockwise direction about its axis and as a result will swing the arms 260 and 262 forwardly to move roller 234 toward the front of the machine. Arms 252 and 254 are carried forward by the abutting engagement of links 258 with links 250. A pin 306 on arm 262 is positioned in a relatively wide notch 308 formed in arm 254, its purpose being to insure that forward roller 232 is fully returned after a cigarette has been rolled. Under normal conditions it will be so returned by a spring 310 interconnecting arms 254 and 262.

Extending into the path of travel of pin 282 is a bar 312 pivoted on a stud 314 fixed in side plate 22. Through a pin and slot connection 316, bar 312 is joined to a bell crank arm 318 which is fixed to a shaft 320 extending transversely through plates 22 and 24. An upwardly directed tensioning plate 322 is secured by screws 324, or the like, to shaft 320 for assisting tensioning roller 226 to retain narrow tapes 228 in tautened condition during the cigarette rolling process as shown in Fig. 10. Arm 318 is held in normal position (Fig. 3), by a spring 319.

In this machine, as in other devices of similar character, it is desirable to incorporate means necessitating complete downward and upward movements of the operating crank and for this reason plate 274 is provided with a notched, arcuate face 326 adapted to be engaged by a pawl 328 pivoted on stud 314, said pawl being urged against face 326 by a spring 330.

The case for enclosing the above described machine is shown completely only in Fig. 1, and comprises a pair of side members 340 and 342, a cover 344 having an opening 346 in registry with supply hopper 42, and end closure strips 348. Side member 342 is provided with an opening 350 (Fig. 15) to allow threading of the paper 150 between the feed and tensioning rollers, the opening 350 being normally closed by a swingable cover 352. Side member 340 is suitably apertured to admit a sleeve portion 354 of crank 48 having key projections 356 for seating in key slots 358 of crank plate 274 (Fig. 12). Both side members 340 and 342 are mounted on the elongated heads 31 by screws 360.

From the foregoing description it will be clear that during a downstroke of the crank 48, a measured quantity of tobacco is discharged from the supply hopper and delivered to the receiving pocket of tape 142, whereupon outlet 47 is closed. Also, during the movement of the crank a length of paper 150 is advanced onto the belt 142 and severed by knife 200. During the upstroke of crank 48, rollers 232 and 234 are carried forward to roll a cigarette and are fully returned by the end of said upstroke.

A special type of paper stock having strips of adhesive along each side edge, with one strip on the upper surface and the other strip on the lower surface of the paper, is best adapted for use in this machine. Such paper and apparatus for producing it are described in an application Serial No. 463,125 filed by me on even date herewith and entitled Paper gumming apparatus.

Having thus described the invention, what is claimed as new and desired to be secured by Letters Patent is:

1. Apparatus for making cigarettes, comprising a tobacco supply hopper having a bottom; a side wall having a serrated lower edge spaced from the bottom to form a discharge opening; a gate in sliding relation with said wall adjacent its lower edge; a plunger movable into the hopper; means for simultaneously opening the gate and moving said plunger into the hopper to discharge a quantity of tobacco through said opening; means for quickly closing the gate to shear shreads of tobacco projecting through the serrations of said lower edge; a holder for a supply of cigarette paper; a table adjacent to the holder; means for advancing a length of said paper onto the table; means for severing said advanced length from the supply of paper; and means for gathering said quantity of tobacco and rolling it into said length of paper to form a cigarette.

2. In apparatus of the character described; a housing including a pair of side walls; a tobacco supply hopper in the housing having a discharge opening; means for forcing a charge of tobacco from said opening; a table transversely disposed

35 in the housing having a portion of one of its side edges spaced from an adjacent side wall of the housing to form a slot; a tape overlying the table; a spool for cigarette paper; a cutter bar in the side wall of the housing adjacent said slot; means for feeding a length of paper from the spool across the cutter bar and onto the tape; a knife mounted for movement through said slot in shearing relation with the cutter bar; means for actuating the knife to sever said length of paper from the supply of paper on the spool; and means including said tape for gathering the charge of tobacco and surrounding said charge with said length of paper to form a cigarette.

3. In apparatus of the character described; a housing including a pair of side walls having registering slots; a tobacco supply hopper in the housing having a discharge opening; means for forcing a charge of tobacco from said opening; a table in the housing; a tape overlying the table; a spool for cigarette paper; means for feeding a length of said paper from the spool through the slot in one of said side walls onto the tape above the table; a roller movable along the upper surface of the tape; a roller movable along the lower surface of the tape, said rollers being each provided with shaft ends projected through said slots in the side walls; and mechanism including said tape and rollers for gathering the charge of tobacco and surrounding said charge with said length of paper to form a cigarette between the rollers.

JOHN C. WAHL.
